LOOSE LEAF BINDER

John Schade, Holyoke, Mass., assignor to National Blank Book Company, Holyoke, Mass., a corporation of Massachusetts

Application October 22, 1936, Serial No. 107,028

5 Claims. (Cl. 129—17)

This invention relates to a combination in a loose leaf binder of improved mechanism for moving the binder prongs. It is particularly constructed to make it easy to arrange visible index bookkeeping sheets, in the binder. The invention also relates to certain detail constructions in the binder to make it easy to handle, particularly in closing the book. Other detail constructions for various purposes in the improved binder will be described and claimed.

According to one principal feature of the invention I provide mechanism for predetermining two particular cycles of prong moving operations. One cycle is to spread the prongs, shift the prongs on one side with respect to those on the other side, and close the prongs again in shifted position. The other cycle is identical, except the prongs are shifted in the opposite direction to the shifting step in the first cycle. The steps of each cycle are predetermined in the sense that the mere operation of the mechanism, as by repeated movements of a handle, will cause first one cycle of operations and then the other, all without any need of the user's attention beyond the mere act of a pull or push on the operating handle.

The means by which this and other features of the invention can be accomplished are illustrated in the accompanying drawings. They will be described in sufficient detail to enable one skilled in the art to understand how to practice the invention.

Referring to the drawings:

Fig. 1 is a top plan view of an open loose leaf binder embodying my invention as it may appear when ready for normal use;

Figs. 2, 3, and 4 are fragmentary views of the structure of Fig. 1 showing the steps involved in the prong moving operation;

Fig. 5 is an enlarged top plan view of the binder in Fig. 1 but with parts of the covers omitted and with the sheets removed;

Fig. 6 is a section on line 6—6 of Fig. 5;

Fig. 7 is a view similar to Fig. 6 but with the binder parts indicated as open ready for the insertion of additional sheets;

Figs. 8 and 9 are bottom plan views of the two back members of the binder with certain parts broken away for clarity;

Fig. 10 is a vertical section on line 10—10 of Fig. 5; and

Fig. 11 is an end view of the structure shown in Fig. 5 but with the binder parts indicated as in closed position.

The general character of visible index book-

keeping sheets and a binder is indicated in Fig. 1. The sheets shown are shorter than the binder. They overlap in stepped relation so as to expose on each a sufficient margin for index purposes. These are indicated by letters A, B, etc.

Suppose the user wants to move sheets E and F up closer to sheet D. The idea is to close the extra gap (not needed for index purposes) between these sheets and sheets A, B, C, and D; also to provide an extra gap between sheets F and H. Then a new sheet G may be inserted and the visible index sheets will appear in uniform order from A to N inclusive. The supposed new arrangement is just a simple illustration of one rearrangement of sheets that may be desired.

To accomplish such a rearrangement, sheets A, B, C, and D are turned over from the right to the left-hand side of the binder. Then the prongs 1 and 2 are spread apart to a position as indicated in Fig. 2. They are then shifted to a position as indicated in Fig. 3. They are then closed to a position as indicated in Fig. 4. In this position sheets E and F are turned over from the left to the right-hand side of the binder. The prongs are now again spread apart as in Fig. 3, shifted back to the position of Fig. 2, and closed again as in Fig. 1. The result is that sheets E and F have been rearranged in the book as desired and without removing these sheets from the prongs. The shifting of only two sheets E and F is mentioned in the illustration; but in the use of such binders it may be desired to shift, for example, as many as twenty sheets at a time, and this can be done without taking the sheets off the prongs. In the full use of a visible index bookkeeping binder, in which, over a period of time, a great many rearrangements of sheets are made by the bookkeeper, the convenience in making them according to the above simple illustration is very great; and prior art binders have long been in use for accomplishing this general purpose of shifting the sheets on the prongs without taking the sheets off the prongs.

In the prior art constructions, so far as I am aware, while the prong movements were made possible, it has been necessary for the user to get the desired cycle of movements in his head and to manipulate by hand each step of the operating cycle independently of each other step or substantially so, and the user had both to learn how and then acquire the necessary skill to carry out the steps of the cycle without bungling. These bookkeeping binders are for the most part large, heavy, cumbersome books.

To improve the binder, I have provided mech-

anism operable by simply pulling handle 3 from the position of Fig. 1 to that of Fig. 4 to automatically perform one desired cycle of operations. This cycle is to spread the prongs, as in Fig. 2, 5 shift them, as in Fig. 3, and close them in shifted position as in Fig. 4. This is all automatically accomplished upon one pulling movement of handle 3, so all the operator has to do, starting from Fig. 1 condition, is turn over sheets A, B, 10 C, D, and then pull handle 3. In the position of Fig. 4 he now turns over sheets E and F, which were shifted upwardly in the book when prongs 2 were shifted upwardly. He now pushes handle 3 back to the position of Fig. 1, resulting in an 15 automatic operation of the mechanism to spread prongs 1 and 2, shift them back to the relative positions of Fig. 2, and close them to the position of Fig. 1 when the sheets A-F appear 20 consecutively spaced as indicated by the dotted position of these sheets. Prongs 2 are the ones which actually move in the shifting step, while prongs 1 remain stationary except as they spread and close. Thus, the sheets E and F are shifted 25 upwardly in the book, by simply turning the sheets and by one pull and one push on handle 3 as the operating handle for the automatic mechanism.

The operating cycles have been referred to as the movements of the prongs 1 and 2. Now it is 30 clear that these are the movements desired; the automatic mechanism and the purpose of each specific element in the combination will be more easily understood. These will now be described.

In the embodiment shown, the back of the 35 binder (Figs. 6 and 7) is made of two angle plates 4 and 5 hinged at 6. A spring 7 with latch pin 8 is mounted on plate 4. When the parts are turned on hinge 6 from positions of Fig. 7 to Fig. 6, latch pin 8 passes along a slot 59 in a movable plate 12 (Fig. 7) and snaps under shoulder 9 in a cam slot 10 of spring plate 11. The latter normally lies flat against plate 12 to which it may be riveted at points 13. Finger piece 14 is for lifting up spring plate 11 to disengage pin 8 from the shoulder 9 when one desires to open the book back completely as in Fig. 7. Plate 11 will return to flat position, ready to have pin 8 snap into the cam slot 10 when the book is moved to position of Fig. 6.

50 A piano hinge plate 15 which carries prongs 1 is fastened to plate 4, while its companion plate 16 is fastened to the left-hand cover 17. The cover hinge is on pintle 18, joining plates 15 and 16. As indicated at 19, there are struck-up portions on plate 16 which overlie the hinge on hinge plate 15. These portions 19 permit the stiff cover 17 and plate 16 to swing outwardly, but as soon as they turn up to a position in the plane of plate 15, the parts 19 engage such plate. Then 55 the latter must turn inwardly with plate 4 on pivot 6, when the cover is turned clockwise—Fig. 6.

The cover hinge construction on the right-hand side (Fig. 6)—as 21, 23, 24 and 22 for cover 60 20, is similarly arranged. The hinge plate 24 on this side lies between a movable or sliding plate 25 (which carries the prongs 2 on the right-hand side of the book), and the outer portion of angle plate 5. The plate 25 is held as in a groove by ears 26 bent into the position shown out of the sheet metal of hinge plate 24. This construction can be seen from Fig. 5 where alternate ears are bent out of hinge plate 24 around pintle 22 and the intermediate ears are bent as hooks 26 over 65 the top edge of plate 25 to guide the latter as in a

slot. Holes 27 in plate 25 permit angle plate 5 to be riveted to hinge plate 24 after the assembly of parts. The rivet heads are countersunk in hinge plate 24 to permit plate 25 to slide on hinge plate 24. 5

The bottom edge of plate 25 has a tongue 28 (Fig. 5) movable in a slot 29 in plate 5. The same edge also has a short set of rack teeth 30 extending through another slot 31 in angle plate 5. The rack teeth 30 are in mesh with teeth 32 of a rocker arm 33 pivoted at 34 (Fig. 9) on the under side of plate 5. The limits of movement of plate 25 and consequently rocker arm 33 are determined by the motion of tongue 28 and rack teeth 30 in the slots 29 and 31 respectively. The 15 rocker arm is operated by the engagement of pin 35 against the walls of recess 36, which pin 35 is fast on the under side of plate 12. The latter is 20 slideable back and forth on plate 5 by pulling and pushing handle 3 at the end of the plate. This plate 12 has two spaced tongues 38 riding in spaced slots 37 (Fig. 9) with bent ends on the tongues to hold plate 12 for its sliding movement on plate 5. Slots 37 (Fig. 9) end in rectangular 25 openings 42 and 43 through which the tongues 38 are dropped in assembling the structure. The 30 cut-out portions 40 and 41 in plate 4 (Fig. 5) are merely for preventing interference when the 35 rocking bar or plate 33 and pin 35 are moved into 40 completely book closed position, indicated in Fig. 45 11.

Now the specific operation of the parts can be described, starting from the closed book position of Fig. 11. When the book is laid on a desk and the covers opened, its weight will carry the back 35 parts to the position of Figs. 1, 5 and 6 with back plates 4 and 5 turned slightly on the back hinge 6. The parts 60 and 61 in Fig. 6 indicate a molded and decorative "false" back or bottom to cover 40 up the mechanism associated with back plates 4 and 5. The position of Figs. 1, 5 and 6 is the flat, 45 normal, writing, reading, or working position of the book.

When handle 3 is pulled out from the position 50 of Fig. 5, it slides plate 12 longitudinally of plate 45 5. Cam slot 10 (in spring portion 11 on plate 12), all carried by plate 5, acts on pin 8 carried by plate 4 to spread plates 4 and 5 apart, turning on hinge 6. Since prongs 1 and 2 are respectively 55 supported on these plates, they are spread apart. When the pin reaches the intermediate portion of the cam slot, the spreading action stops. As it 60 stops, the pin 35 on plate 12 engages recess 36 and while pin 8 is riding in said portion of the cam slot, pin 35 is turning rocking plate or bar 33 on pivot 34, for teeth 30 to move teeth 30 on the rack bar of plate 25. The latter carries and 65 thus shifts all the prongs on the right-hand side of the back supported by plate 5 on which plate 25 slides. As pin 8 finishes its path in the intermediate portion of cam slot 10 (the cam slot 70 has been moving here rather than pin 8) and enters the upper slanting cam slot portion, the pin 35 leaves recess 36 and sliding movement of plate 25 stops. But as it stops, cam slot 10 begins to 75 move pin 8 to bring the back plates 4 and 5 together again to the position of Fig. 6 from which they started. The finish of this movement occurs as the pin 8 contacts the upper or innermost end of the cam slot. This completes one cycle of 80 operating steps in moving the prongs in one automatic predetermined series of steps. When the handle 3 is pushed back, an identical operating cycle occurs except that the prong set on plate 25 is shifted in the reverse direction to the prong 85 90 95 98 99 100

shifting (as distinguished from prong spreading and closing) step in the first cycle.

During both cycles it will be seen from Fig. 1 that pin 35 rides over a straight edge of rocker plate 33 without moving the latter until it engages the walls of recess or notch 36. The parts are designed preferably as shown, with tongue 28 and slot 29 and rack teeth 30 and slot 31 locking rocker 33 against movement while either 10 end portion of cam slot 10 is functioning to move pin 8 transversely and to permit movement of rocker 33 only while the intermediate portion of cam slot 10 is functioning to prevent transverse movement of pin 8. The mechanism is preferably interlocked with respect to the described 15 sequence of operations.

When it is desired to open the book with prongs further apart than they ever are in the described predetermined cycles of operation, the user may 20 lift up spring portion 11 by finger piece 14, see Fig. 5. This frees the latch pin 8 from shoulder 9 of cam slot 10 and the parts can be moved to the position shown in Fig. 7. It will be noted that the latch pin 8 can escape along slot 59 only 25 when the handle 3 is in the normal reading position of Fig. 5 which prevents accidental opening of the book to position of Fig. 7 while the shifting cycle is being carried out. From this position one can simply lift the covers, and by the action 30 of tongues 19 and 23 swing plates 4 and 5 on pivot 6 for pin 8 to snap again into cam slot 10. Furthermore, when it is desired to close the book up from reading position to the storage position of Fig. 11 this can be done by simply lifting the 35 covers 17 and 20. If it were not for tongues 19 and 23 arranged as they are in the combination, the user would be inconvenienced by having to manipulate the parts hinged at line 6, Fig. 7, to get them into position for closing the book. 40 The covers 17 and 20 hinged at 18 and 22 would not ordinarily be able to move the parts hinged at 6.

The end plate 50 in Fig. 11, together with the handle 3, helps make end cover plates for 45 the loose leaf mechanism to give good appearance, and when the book is closed as in Fig. 11 the lower edges 57 of plates 11 and 12 abut plate 50 to prevent accidental movement of the handle 3. With the book on the table, one hand can take 50 hold of flange 50 while the other hand pulls or pushes on handle 3.

The sets of prongs should be arranged to be spread out of overlapping relation with respect 55 to the sheets on the prongs opposite to each set. When the ends of the prongs in each set are moved out of the holes of the sheets on the opposite set, the prongs can be shifted without interference. This condition depends on the number of sheets carried and at what part of the 60 sheet pack the book is opened for shifting. Consequently when I refer in the claims to the prongs being moved out of full overlapping relation, I mean that they are moved far enough out of their normal overlapping relation and not necessarily out of actual overlapping relation, for the shifting function to take place without interference with the sheets. When the operation is to open near the center of the book, a condition can be attained for shifting where the tips of 65 each prong set are exposed.

It will be noted that according to the preferred method of operation, see Figs. 1-4, the sheets A-N are turned from one side of the book to the other in a shifting operation only when the 70 prongs 1-2 are overlapped, while when the

prongs are moving longitudinally they are not overlapped. By this construction and cycle of operation the book can be literally "stuffed" with extra sheets, and when the prongs are moved longitudinally there is no danger of the holes in the 5 sheets being torn, while when the sheets are being turned after the shift the prongs overlap enough to guide the sheets readily from one set of prongs to the other.

This arrangement makes an extremely good actuating means for the automatic mechanism built into the book. The mechanism needs no teaching or acquired skill on the part of the operator. All he needs to do is to turn over his sheets, push and pull on a handle. It is all so simple and convenient in operation that the improved binder gives what has long been needed in this book-keeping field for visible index sheet work.

I claim:

1. A binder having centrally pivoted back portions and a set of prongs supported from each back portion, one of such sets being mounted for longitudinal movement between two offset positions relatively to the other set, and cam mechanism operable to move relatively the pivoted 20 back portions and one set of prongs between said offset positions all in sequential operation whereby the prongs are spread, offset, and overlapped in alternate offset positions upon successive operations of said cam mechanism.

2. A binder having a back portion including two hingedly connected plates, a set of prongs supported at the side edge of each plate, a slideable bar carrying one set for movement longitudinally of the plate, said bar having rack teeth, a pinion on one back plate engaging said teeth, a slideable cam plate on one back plate for operating said pinion and means connecting the other plate to said slideable cam, whereby upon sliding the cam the prong sets are moved back and forth 35 transversely of the binder and one set is moved longitudinally of the other in sequential operation.

3. A binder composed of two back plates, each having an upstanding flange at the outside edge 45 and a depending flange at the inner edge, a hinge connecting the lower edges of the depending flanges, a set of prongs supported from each upstanding flange, a slideable plate carrying one of said sets, a device the position of which determines the relative position of the back plates on their hinge, and mechanism operable to move said device and said slideable plate in sequential operation whereby the relative position of the prongs 50 in the binder is changed for sheet manipulating 55 purposes.

4. In a binder construction for visible index sheets, two sets of oppositely disposed prongs, relatively movable prong supports mounted in the binder to permit one set of prongs to be moved to and from two overlapped positions as well as to and from two offset positions relatively to the other set of prongs for sheet binding and index shifting purposes in the binder, constraining means cooperating with one of the prong supports to require the change in said overlapped positions to take place transversely of the binder while no change is taking place in said offset positions and the change in the offset positions to 60 take place while no change is taking place in the overlapped positions, and an actuator operable in one direction to push or in an opposite direction to pull the prong support for coaction against 65 said constraining means, for a sequential operation 70 while no change is taking place in the overlapped positions, and an actuator operable in one direction to push or in an opposite direction to pull the prong support for coaction against 75 said constraining means, for a sequential operation.

ation of first changing relative overlapped positions, then offset positions, and then overlapped positions of the prong sets according to the aforesaid requirement of said constraining means.

- 5 5. In a binder construction for visible index sheets, two sets of oppositely disposed prongs, relatively movable prong supports mounted in the binder to permit one set of prongs to be moved to and from two overlapped positions as 10 well as to and from two offset positions relatively to the other set of prongs for sheet binding and index shifting purposes in the binder, constraining means cooperating with one of the prong supports to require the change in said

overlapped positions to take place transversely of the binder far enough to open the prongs for the ends thereof to be free of index sheets while no change is taking place in said offset positions and then to allow the change in the offset positions to take place, and an actuator operable in one direction to push or in an opposite direction to pull the prong supports for coaction against said constraining means, for a sequential operation of first changing relative overlapped positions, then offset positions, and then overlapped positions of the prong sets according to the aforesaid requirement of said constraining means. 5 10

JOHN SCHADE.
